UNITED STATES PATENT OFFICE.

CYRUS KEHR, OF LAKESIDE, ILLINOIS.

MACHINE FOR AND METHOD OF WEAVING COILED-WIRE FABRIC.

SPECIFICATION forming part of Letters Patent No. 511,435, dated December 26, 1893.

Application filed September 8, 1892. Serial No. 445,883. (No model.)

To all whom it may concern:

Be it known that I, CYRUS KEHR, a citizen of the United States, residing at Lakeside, in the county of Cook and State of Illinois, have 5 invented certain new and useful Improvements in Machines for and Methods of Weaving Coiled-Wire Fabric; and I do hereby declare the following to be a full, clear, and exact description of the invention, such as will 10 enable others skilled in the art to which it appertains to make and use the same, reference being had to the accompanying drawings, and to letters of reference marked thereon, which form a part of this specification.

15 My improvement consists in certain additions to and improvements of such machines and methods as are described in Letters Patent of the United States No. 348,150, granted to Orlando P. Briggs, August 24, 1886; No. 20 480,007, granted to O.P. Briggs and F.L. Bryant, August 2, 1892; and No. 463,993, granted to me November 24, 1891. My improvement is also applicable to what are termed hand machines; namely, machines in which the 25 coil-forming mechanism is operated by hand and the fabric is formed upon a table and shifted and controlled by hand upon said table and the coils are cut by hand. In other words, the mechanism involved in my im- 30 provement is to be so geared as to operate automatically in conjunction with the coil-forming mechanism. Whether the remainder of the work is performed automatically, is im- 35 material so far as my improvement is con- cerned.

What is termed coiled wire fabric is formed by pushing the wire through a spiral passage, whereby it is formed into a spiral, to a sufficient distance to form the length of the fabric, and then cutting off the coil and forcing 40 more wire through the spiral passage and causing the second coil to intertwine with the first at each turn, then cutting the second coil and forming a third and causing it, 45 while being formed, to intertwine with the second. Heretofore, in the insertion of the new or in-coming coil into the last-finished or marginal coil of the fabric, the strength of the wire of which the coil has been composed 50 has been solely relied upon to effect the pro-

gression of the coil and devices designed to keep the coil in the proper course to intertwine with the marginal coil were relatively stationary and therefore passive in character and dependent for effectiveness upon the 55 strength of the coil. It has been found that friction and the flexibility and pliability of the wire prevent this method from being perfect. The unavoidable variation in the pitch of the coils is also an element operating 60 against the success of this method; for, if the in-coming coil differs in pitch from the marginal coil, the end of the in-coming coil will meet the turns of the marginal coil or any faces of parts of the machine concerned 65 in holding and shifting the marginal coil and be deflected or stopped thereby.

According to my improvement, the end of the in-coming coil is engaged and guided or led through its proper path. By this method 70 the insertion of the new coil is not dependent upon the strength of the wire, but upon the operation of the mechanism employed in engaging and leading the forward end of the coil.

The essential part of the apparatus for practicing my improved process may be termed a spiral needle, which is inserted into the path to be traversed by the in-coming coil and then made to engage the end of the in- 75 coming coil and travel synchronously with the latter from the coiler spirally through the turns of the marginal coil.

The accompanying drawings show my improvement applied to such a machine as is 80 illustrated in said patent to Briggs and Bryant, No. 480,007.

In said drawings, Figures 1 and 2 constitute a vertical sectional view of the machine, the machine being of such length as to require 85 two sheets for one view. Figs. 3 and 4 constitute, in a similar manner, a plan of the same machine. Fig. 5 is a vertical section in the line a—b of Fig. 3 looking in the direction of the arrow. Fig. 6 is a plan of the coil-forming mechanism. Fig. 7 is a detail of the rolls and guides concerned in forcing the wire through the spiral passage. Figs. 8, 9, and 10 are details of the needle, coils, and knife. Figs. 11 and 12 show alternative means for 90 95 100

rotating the needle. Fig. 13 shows a detail of the mechanism for reciprocating the marginal coil longitudinally.

In said drawings, A is a frame upon which 5 the operative parts of the machine are supported. Said frame is a little more than twice as long as the length of the fabric to be woven.

A' is a horizontal carriage supported by 10 wheels, A², arranged at each corner of said frame and resting in ways, A³, fixed upon the frame, A, parallel to the length of said frame. The same result may be obtained by applying 15 the wheels, A², to the frame, A, and the ways, A³, to the carriage, A'. The object of said wheels and ways is to provide a limited longitudinal reciprocation of the carriage, A', as and for the purposes hereinafter set forth.

B is a band-wheel mounted loosely upon a 20 driving-shaft, B', which shaft is supported in bearings, B², suitably located upon one end of the frame, A.

B³ is a bevel-gear loosely surrounding the shaft, B', and secured to the wheel, B, and B⁴ 25 is a bevel-gear meshing into the bevel-gear, B³, and surrounding and keyed to the worm-shaft, B⁵, which worm-shaft engages the worm gear-wheel, B⁶, and imparts rotation to the latter. The worm-gear, B⁶, surrounds and is keyed to 30 a horizontal shaft, B⁷, and upon said shaft, B⁷, at one side of the worm-gear wheel, B⁶, and keyed to said shaft, is a spur-gear, B⁸, meshing into a small spur-gear, B⁹, mounted upon and keyed to the horizontal shaft, B¹⁰. Surrounding the shaft, B¹⁰, is a cam-wheel, B¹¹, 35 provided with two cam-faces, b¹¹.

B¹² is a clutch-lever pivoted between its ends, as at b¹², and having its upper end in engagement with a clutch, B¹³, which is keyed to the 40 shaft, B', and adapted to engage the band-wheel, B, so that motion may be transmitted from said band-wheel to said shaft, B'. The relation of said band-wheel, clutch-lever, B¹², and cam-wheel, B¹¹, is such that when the 45 clutch, B¹³, is thrown into engagement with the band-wheel, B, the lower end of the arm, B¹², will be in the path of the cam-faces, b¹¹, and ready to be moved by the latter when they pass said end. The said clutch is held 50 normally in engagement with said band-wheel by an expanding coiled spring, B¹⁴. (See Figs. 4 and 6.)

From the foregoing it will be seen that if the band-wheel, B, is rotated continuously the 55 gears, B³, B⁴, worm-shaft, B⁵, worm-gear, B⁶, shaft, B⁷, spur-gears, B⁸, and B⁹, shaft, B¹⁰, and cam-wheel, B¹¹, will be operated continuously, while the clutch-lever, B¹², clutch, B¹³, and shaft, B', will be operated intermittently, 60 and that the interval during which the shaft, B', rotates will hold the same ratio to the interval during which it does not rotate as the ratio of the spaces between the cam-faces, b¹¹, holds to the length of said faces. For example, if the length of each cam-face is only one-

tenth of the space between the two cam-faces, the interval during which the shaft, B', does not rotate will be only one-tenth as long as the period during which it does rotate. The object in providing these continuous and intermittent movements is to afford means for 70 periodically arresting the action of the coil-forming mechanism and at the same time provide continuously-moving parts which may be treated as a source of movement for other 75 portions of the machine which are to operate during the suspension of the operation of the coiling mechanism.

For convenience, the coil-forming mechanism will be termed the coiler. This is designated by the letter C. As any suitable form of coiler may be used in connection with the other parts of the machine, and as a variety of coilers are already known to those familiar with this art, it is deemed sufficient to herein 80 describe one of said coilers as to merely its general features. From the base, C', rise four bearing-posts, C², each of which has extending from its upper end downward through its middle a space in which are the bearing-blocks, C³. Said bearing-blocks, C³, form bearings for the horizontal parallel shafts, C⁴ and C⁵, C⁴ designating the lower of said shafts and C⁵ the upper of said shafts. Said shafts are geared to each other by spur-gears, C⁶, applied, 85 respectively, to the shafts, C⁴ and C⁵.

C⁸ is a spur-gear located upon the shaft, C⁴, and meshing into another spur-gear, C⁹, suitably supported between the shafts, C⁴ and B', and in turn meshing into a spur-gear, B¹⁵, 90 mounted upon the shaft, B'. Upon the middle of the shafts, C⁴ and C⁵, are located wire-forcing rolls, c⁴ and c⁵, respectively, which rolls bear upon each other and are turned when said shafts are rotated. The two middle posts, C², terminate above in arches, C¹⁰, and a vertical screw, C¹¹, extends downward through each such arch and bears upon an expanding spring, (not shown,) which spring in turn bears upon the bearing-block, C³, located in the adjacent bearing-post, C². The lower bearing-blocks, C³, have fixed positions in the lower portions of the channels or vertical spaces in the posts, C², so that the positions of the spur-gears, C⁶, and the wire forcing roll on the shaft, C⁴, are unyielding. Driving the screw, C¹¹, downward will cause the spring, C¹², to press the adjacent upper bearing-block, C³, downward upon the shaft, C⁵, and said shaft will be pressed down so that 100 the upper wire-forcing roll and the spur-gears upon said shafts will be forced together.

C¹³ is a guide for leading the wires, f, to the wire-forcing rolls, and C¹⁴ is a guide to lead the wire from the forcing-rolls to the coil-forming spindle, C¹⁵. Said coil-forming spindle has around it a spiral passage and a shell, C¹⁶. The wire is forced through said spiral passage between said spindle and said shell and is thereby transformed into a coil, which 110 115 120 125 130

passes off over the end of the spindle, C¹⁵, into the channel, D, to be hereinafter described.

D is a channel formed in the upper portion 5 and lengthwise of the carriage, A', in line with the spindle, C¹⁵, so as to receive the needle, N, and the coil projected from the coiler, C, and at the side of said channel is a wall, d, to aid in retaining said coil and needle.

10 D' is a roller mounted upon and extending lengthwise of the frame, A, at the rear of the channel, D, and arranged to be rotated, as will be hereinafter described.

D² is a roller located above and parallel to 15 the roller, D', and having its journals resting loosely in vertical guide-ways, D³, so that it will rest by gravity upon the roller, D', or upon the woven-wire fabric, F, when the latter lies between said rollers. The roller, D', 20 is rotated in the direction indicated by the arrow, and, together with the roller, D², serves to draw the coiled fabric away from the line in which the coils are formed.

The shaft, B¹⁰, which has already been described as rotating continuously, has surrounding it rigidly the spur-gear, B¹⁴. Beneath, parallel to, and extending along the entire length of the carriage, A', is a shaft, E, which receives motion from the spur-gear, 25 B¹⁴, through the spur-gear, E', with which it meshes and which surrounds and is keyed to the shaft, E.

At the left end or foot of the machine, a mutilated gear, E³, surrounds and is secured 30 to the shaft, E. Said mutilated gear has upon its periphery four equidistant teeth, e³. The roll, D', has at the foot end of the machine a spur-gear, D⁴, which is in plane with the mutilated gear, E³, and of proper diameter 35 to have its teeth reach into the path of the teeth, e³, of said mutilated gear. The rolls, D', and D², may or may not be provided with intermeshing gears like the one shown at D⁵, Fig. 4. It will now be seen that with 40 each quarter rotation of the mutilated gear, E³, the rolls, D', and D², will be rotated through a few degrees. The extent of this rotation of said rolls is sufficient to move a point in the circumference of one of said rolls through a 45 distance equal to the diameter of one of the coils of the fabric, the precise distance being attained by establishing the proper ratio of difference between the mutilated gear, E³, and the spur-gear, D⁴. The length of the 50 intervals between these partial rotations of the rolls, D', and D², is dependent upon the velocity of the mutilated gear, E³, and the gears intervening between said mutilated gear and the band-wheel, B.

55 60 In starting the machine, the fabric, F, is managed by the operator until enough has been formed to be properly engaged by the mechanism of the machine. Then the marginal or last-finished coil is held parallel to 65 and partially in the groove, D, by the pins, G', of the pin-bars G, the pins G', one of

1 said pin-bars standing in the coil next to the marginal or final coil and bearing against both of said coils, and the rolls, D', and D², tending to draw the fabric away from said 70 pin-bar. (See Figs. 8 and 9.) By this means every marginal coil is brought with great accuracy into the desired relation with the coiling-axis, or the line which coincides with the axis of the new coil as the latter is being projected from the coiler, so that every 75 turn of the marginal coil is in the precise position best adapted to allow the new coil to intertwine at each rotation with said turn. The groove or channel, D, is thus in accurate 80 relation with every turn of the marginal coil, and the needle, N, in being projected through said groove toward the coiler is guided at every turn into precise relation with each turn of the final coil. As soon as a coil is 85 completed and cut adjacent to the coiler, the pin-bar, G, then in engagement with the fabric must be released, in order that the fabric may be drawn from the coiling-axis by the fabric-drawing mechanism, and at the same 90 time the other pin-bar, G, must be brought into proper relation to engage the coil next succeeding the one which was last engaged by said pin-bar. This is accomplished by alternating the elevation of said pin-bars with 95 one another. Immediately after the last-finished coil is cut adjacent to the coiler, the pin-bar then in engagement is lowered, while immediately following this change, the pin-bar ascends and the other pin-bar descends 100 and moves into the path of the coil next succeeding the one last engaged and arrests the movement of said succeeding coil, whereby the movement of the entire fabric is arrested.

The upper pin-bar, G, is located beneath 105 and has its pins, G', rising through the openings, g, in the top of the carriage, A'. The lower pin-bar, G, is located beneath the upper pin-bar and has its pins, G', rising through the upper pin-bar between the pins, G', of the upper pin-bar and through openings, g, in the top of the carriage, A'. Each of the pin-bars, G, has a vertical support G⁴ resting upon a cam, G², on the shaft, E, the extended portions of the cams which receive the supports from one pin-bar alternating in radial relation with the extended portion of the cams supporting the other pin-bar, so that as the shaft, E, is rotated, the pin-bars, G, are alternately elevated, whereby the pins on the respective 110 bars, G, are alternately extended upward through the top of the carriage, A', into the path of the coils of the fabric, one set of said pins always rising through the top of said carriage, while the other set of said pins is being drawn downward through said top.

115 G³, G³, are depending arms attached by their upper ends to the carriage, A', close to the sides of the pin-bars and serve to so confine the bars, G, as to allow the latter to move only 120 in a vertical plane. (See Fig. 2.) If so desired, such knife-bars as are described in said 125

patent to Briggs and Bryant, No. 480,007, may be placed upon the machine in proper arrangement to co-operate with the pin-bars, G, as described in said patent.

5 The mechanisms leading from the shaft, E, to the pin-bars, G, and from said shaft to the rolls, D', and, D², are properly timed with reference to each other to produce the necessary simultaneous action.

10 Attention is now asked to the mechanism for periodically shifting the carriage, A', from and toward the coiler. An arm, A³, extends from said carriage toward the shaft, E, and there supports two rollers, a⁵, one extending 15 to each side of the periphery of a cam, J, and each presenting to said cam a face to which the line of movement of the carriage is substantially perpendicular. Said cam is duplex, being composed of two disk-form sections, J', 20 each loosely surrounding and separately adjustable upon the shaft, E, by means of set-bolts, J², and having on the face toward the adjacent roller, a⁵, one or more cam faces, j', the cam face or faces on the one section, J', 25 alternating in radial spacing with that of those on the other section. The sections, J', of the duplex cam, J, are separated sufficiently to cause each roller to be pressed laterally by the passing of the cam-face on the other 30 cam-section, so that when said other cam-face, J', is rotated past the second roller the movement is reversed. Thus the carriage, A', is alternately shifted upon the ways, A³, a distance equal to the difference between 35 the distance between the rolls, a⁵, and the thickness of the cam, J, from the plane of the cam-faces at one side of the cam to the plane of the cam-faces at the other side of said cam. This distance may be varied by shifting the 40 cam-sections of the cam, J. The precise path of reciprocation of the carriage, A', may also be varied in location by bodily shifting the cam, J, toward and from the head of the machine upon the shaft, E. The distance through 45 which said carriage reciprocates should be equal to about one-half the distance between the turns of the coils in the fabric, F, in order that such turns may always be brought out of the spiral path through which the new 50 coil is projected, to the end that the new coil may run forward in its path and intertwine at each turn with the marginal or last-finished coil without hitting the latter. The radial position of the cam-faces, j', with reference 55 to the shaft, E, is to be so adjusted as to cause one of said cam-faces to operate immediately after the operation of the knife which cuts the coil adjacent to the coiler.

L is the knife for cutting the wire adjacent 60 to the coiler as often as a coil is completed. L' is a stationary block through which the coil passes as it comes from the coiler and against which the coil is cut by said knife, L. Said knife, L, is attached to a vertically-reciprocating bar, L², confined above in a guide, L³, and extending below through a guide-plate,

L⁴. The lower end of said bar is surrounded by an expanding coiled spring, L⁵, which has its lower end bearing upon said guide-plate and its upper end resting against the shoulders, 70 L⁶, and the expansion of said spring keeps said bar and said knife normally elevated. The knife is preferably formed with a hole, l, converging from the side opposite the coiler toward the coiler and registering normally 75 with the opening through the stationary block, L', in order that the needle, N, may be the better guided to register with the opening in said block, L'. (See Fig. 10.) The new coil is projected through said opening, l, and the 80 downward movement of the knife causes the shearing of the coil. From a point below the level of the shaft, B¹⁰, an anti-friction roller, l⁶, is supported by said bar, L², and extends laterally beneath a cam, L⁶, surrounding the 85 shaft, B¹⁰. As the extended portion of said cam passes between said shaft, B¹⁰, and said roller, l⁶, the latter and the bar, L², and knife, L, are forced downward, so as to cut, and when said extended portion is passed out of 90 engagement with said roller, the latter and said bar and knife are allowed to rise in response to the expansion of said spring, L⁵. The extended portion of said cam, L⁶, is so placed radially upon the shaft, B¹⁰, as to cause 95 the knife, L, to operate immediately after the forcing-rolls of the coiler have rotated a sufficient number of times to project a coil of the desired length and have stopped.

The needle, N, is shown located upon a carriage, O, which carriage is supported by the frame, A, at the end of the latter opposite the coiler, C. Said carriage, O, is arranged in horizontal ways, O', extending lengthwise of the frame, A. The needle, N, has a stem, N', 100 resting in bearings, n', axially in line with the coiling-axis. From this stem the needle extends toward the coiler a distance equal to the length of the fabric to be woven. The spiral turns of the needle conform in direction, pitch, and mean diameter to the direction, pitch, and mean diameter of the coils to be formed, so that said needle may be rotated and simultaneously move toward the coiler through the precise path to be traversed by 105 the in-coming coil. At its free end, said needle is tubular for a short distance, as indicated in Fig. 9, in order that the new coil may enter or telescope with said needle to the extent of a few turns.

O² is a relatively small gear pinion mounted upon the stem, N', of the needle, N.

O³ is a relatively large bevel gear mounted on a shaft, O⁴, located upon the carriage, O, at right angles to the stem, N', so as to allow 115 the bevel wheel, O³, to intermesh with the pinion, O².

O⁵ is a spur-gear mounted on the outer end of the shaft, O⁴, and meshing into a horizontal rack, O⁶, extending lengthwise upon the 120 frame, A, beneath said spur-gear. It will be seen that by reason of this arrangement of

gears, rotation would be imparted to the needle, N, when the carriage, O, is reciprocated; that when the carriage, O, is moved toward the coiler, C, the needle, N, will be progressed 5 bodily toward the coiler and at the same time rotated in the same manner that the new coil is rotated while being projected through the channel, D; that when the carriage, O, is held in the opposite direction, the needle, N, will 10 be moved bodily away from the coiler and at the same time rotated in the opposite direction. Thus the needle, N, may be made to traverse toward the coiler through the precise path to be traversed by the new coil and 15 then retract through the same path.

The carriage, O, should rest during a short interval at each end of its range of movement. Then, when the carriage is at its limit of movement toward the coiler, the needle, N, 20 is resting in proper position to receive the end of the new coil, as shown in Fig. 10. The needle should be thus at rest until the incoming coil has progressed sufficiently to enter the needle. It should then start and move 25 away from the coiler synchronously with the new coil. Then, when the carriage is at the other limit of its movement and the needle has been entirely retracted from the fabric, the needle and carriage will remain stationary 30 long enough to permit the cutting of the wire by the knife, L, and the shifting of the fabric on the pins, G', and the longitudinal shifting of the carriage, A'. This period of rest may, however, be avoided by retracting the 35 needle farther than is necessary to disengage it from the fabric and then returning it, the cutting and shifting above mentioned being effected during the time in which the needle is out of the range of the fabric.

40 Various means may be employed for controlling the carriage, O. In the drawings, I illustrate the bevel gear, P, mounted upon a shaft, B¹⁰, and meshing into a bevel gear, P', on a vertical shaft, P², having suitable bearings in the frame, A, and bearing at its upper end beneath and between the ends of the ways, O', toward the coiler a sprocket wheel, P³. Beneath and between the opposite ends of the ways, O', is a similar sprocket wheel, P⁴, mounted on a vertical shaft, P⁵, also having suitable bearings in the frame, A. An endless sprocket chain extends around the sprocket wheels, P³, and, P⁴, in a horizontal plane. Above a portion of the chain, P⁶, at 45 each side of the sprocket wheels, P³, and, P⁴, the carriage, O, has a depending lug, o, extending almost to said chain. Upon said chain is a lug, p⁶, resting in a horizontal plane of the lug, o. Since the shaft, B¹⁰, has continuous motion, it follows that the sprocket chain, P⁶, must have continuous motion and that the carriage, O, must move whenever the lug, p⁶, is in engagement with one of the lugs, o, the direction of the movement of said carriage depending upon which side of the circuit of the chain the lug, p⁶, at the time occurs.

In Figs. 1 and 3, the lug, p⁶, is shown in contact with the lug, o, at the side of the latter toward the coiler and drawing the carriage away from the coiler. An inspection of Fig. 3 will show that the lug, p⁶, will soon be carrying said ways out of engagement with the lug, o, and around the wheel, P⁴, into the path of the other lug, o. Between the time of the disengagement from the first lug, o, and the 70 engagement with the other lug, o, the carriage is at rest, and the coiling, cutting, and fabric-shifting mechanisms are so timed as to operate during this interval. As soon as the lug, p⁶, engages with the second lug, o, the carriage, O, 75 is set in motion toward the coiler, and the needle is again inserted into the last-finished coil and through the channel, D, to receive the next new coil. In going around the wheel, P³, the lug, p⁶, is disengaged from the lug, o, 80 at that side of the carriage and subsequently re-engaged with the lug, o, at the other side of the carriage. Thus an interval of rest is afforded during which the coiler may be started and a new coil driven into the tubular end of the needle, N, before the needle is 85 retracted.

The sprocket chain may, obviously, be replaced by any other form of endless band, but I recommend the sprocket chain as being 90 more precise in its operation.

It is to be noted, that the needle, N, may be made of a relatively thick and rigid wire, so that there will be little tendency for the free end thereof to depart from the true path on 100 being inserted. At the time of retracting, the entire needle is intertwined with the last-finished coil and cannot depart from the proper path, and because the forward end of the new coil is engaged by the end of the 105 needle, such end of the coil must follow the latter through the proper path.

In Figs. 11 and 12, I show alternative means for rotating the needle as the carriage, O, progresses. In each case the stem, N', of the 110 needle is mounted in bearings, n', as shown in Fig. 3, but the gear wheels, O², and, O³, are omitted. In Fig. 11, a block, Q, is located upon the frame, A, at the ends of the ways, O', toward the coiler and provided with a stationary passage, q, conforming to the diameter and pitch of the needle. Through this passage the needle extends. When the carriage, O, is reciprocated, the needle is forced through said block and rotated. In Fig. 12, 115 a block, R, is located at the opposite end of the ways, O', and the stem of the needle is extended through a stationary grooved passage, r, in said block and has its stationary groove to conform to said passage, r. It will 120 be readily seen, that the reciprocation of the carriage, O, will involve the rotation of the needle by the passage of said extended part of the stem through the block, R.

I claim as my invention—

1. In apparatus for weaving coiled wire fabric, the combination with a fabric support,

of a spiral needle having a tubular end, and mechanism for rotating and reciprocating said needle substantially as described.

2. In a machine for weaving coiled wire fabric, the combination with mechanism for supporting the fabric, of a spiral needle arranged to engage a new coil and travel synchronously therewith through a path which is intertwined with a coil of the fabric, substantially as described.

3. In a machine for weaving coiled wire fabric, the combination with a fabric support and a coiler, of a spiral needle arranged to traverse the path of the new coil and provided with means for engaging the forward end of the new coil, substantially as described.

4. In a machine for weaving coiled wire fabric, the combination with a support for the fabric, of a coiler located at one end of said support, and a rotary reciprocable needle located at the other end of said support, and suitable connection between said coiler and said needle, whereby motion may be imparted simultaneously to said coiler and said needle from the same source of power, substantially as described.

5. The method of adding a coil to a coiled wire fabric, which method consists in forcing wire through a spiral passage and projecting the resulting coil through a path which is spirally intertwined with one of the coils of the fabric, and engaging the forward end of said new coil by mechanism having motion in the direction of movement of the coil and leading it through said spiral path, substantially as described.

6. In a machine for weaving coiled wire fabric, the combination with a support for the fabric, of a coiler, a knife for cutting the completed coils, and a spiral needle for conducting the new coil, these several mechanisms being arranged to operate automatically and in proper order of time, substantially as described.

7. In a machine for weaving coiled wire fabric, the combination of fabric-supporting and shifting mechanism, coil-forming mechanism, coil-cutting mechanism, and mechanism having motion in the direction of movement of the new coil while the latter is being projected for engaging and conducting the free end of the new coil through its path, these several mechanisms being arranged to operate automatically and in due order of time, substantially as described.

8. In a machine for weaving coiled wire fabric, the combination with a support for the fabric, of a coiler, ways O', carriage O located upon said ways, a spiral needle mounted in suitable bearings upon said carriage in line with the coiling axis, and mechanism for effecting the rotation of said needle simultaneously with the reciprocation of the needle, substantially as described.

9. In a machine for weaving coiled wire fabric, the combination with a support for the

fabric, of a coiler, ways O', carriage O located upon said ways, a spiral needle mounted in suitable bearings upon said carriage in line with the coiling axis, and gearing extending from the frame of the machine to said carriage and needle for rotating the latter, substantially as described.

10. In a machine for weaving coiled wire fabric, the combination with a fabric support and a coiler, of a spiral needle arranged to traverse the path of the new coil and being tubular at its free end, substantially as described.

11. In a machine for weaving coiled wire fabric, the combination with a fabric support and coil-forming mechanism, of a spiral needle, a carriage supporting said needle in line with the coiling axis, gearing intervening between said needle and the frame of the machine for effecting the rotation of the needle, and an endless band located adjacent to said carriage and adapted to engage and reciprocate the latter, substantially as described.

12. In a machine for weaving coiled wire fabric, the combination with a support for the fabric, coil-forming mechanism, and a rotary reciprocable needle arranged to traverse the path of the new coil and conduct the forward end of the latter, of a guide located at the beginning of the path of the new coil, whereby said needle is caused to meet the forward end of the new coil, substantially as described.

13. In a machine for weaving coiled wire fabric, the combination with a support for the fabric, coil-forming mechanism, and a rotary reciprocable needle arranged to traverse the path of the new coil and conduct the forward end of the latter, of a guide combined with a knife and located at the beginning of the path of the new coil, whereby said needle is caused to meet the forward end of the new coil, substantially as described.

14. In a machine for weaving coiled wire fabric, the combination with a coiler, of a fabric support arranged in line with said coiler, and automatically reciprocating devices supported by said support for engaging and releasing the marginal coil of the fabric, and a needle arranged to traverse the path of the new coil and conduct said coil through said path, substantially as described.

15. In a machine for weaving coiled wire fabric for bed-bottoms, the combination with a coiler, of a fabric support arranged in line with said coiler, reciprocating mechanism supported by said support for engaging and releasing the marginal coil of the fabric, and mechanism also supported by said support for drawing the fabric from said reciprocating engaging and releasing mechanism, and a spiral needle arranged to traverse the path of the new coil substantially as described.

16. In a machine for weaving coiled wire fabric, the combination with a coiler, of a series of pins for engaging the marginal coil of the fabric, of a spiral needle arranged to trav-

erse the path of the new coil and conduct the latter through said path, substantially as described.

17. In a machine for weaving coiled wire fabric for bed-bottoms, the combination with coil-forming mechanism and two reciprocating pin-bars, each bearing a series of pins adapted to alternately engage the marginal coil of the fabric, of a spiral needle arranged to traverse the path of the new coil and con-

duct the latter through said path, substantially as described.

In testimony whereof I affix my signature, in presence of two witnesses, this 6th day of September, 1892.

CYRUS KEHR.

Witnesses:

AMBROSE RISDON,
J. H. MCGRUE.
